UNITED STATES PATENT OFFICE

2,028,687

CARTON

Arthur Read, Portland, Oreg., assignor to "Pouring Spouts Inc.", Portland, Oreg., a corporation of Oregon

Application September 8, 1934, Serial No. 743,202

4 Claims. (Cl. 229—17)

This invention relates to improvements in cartons and more particularly to the type of carton shown and described in my United States Patent No. 1,954,576, dated April 10, 1934, which was issued on an application filed by me on July 26, 1932, under Serial Number 624,769 and entitled Pouring spout for containers.

One of the principal objects of the present invention is to provide a pouring spout which, when in a closed position, maintains a sealed relation with respect to two walls of the carton.

Another object of the invention is the method of folding the end flaps of the carton with which my pouring spout is associated, in such a manner that the carton, and particularly the pouring spout, is maintained in a sealed relation to the carton, not only for delivery to the user, but also during subsequent use of the carton with the pouring spout in closed position.

Another object of the invention is the provision of a guideway for one wall of the pouring spout for guiding the same into its sealed relation with the wall of the carton and also to stabilize the spout throughout its range of operation.

These and other objects will appear as my invention is more fully hereinafter described in the following specification, illustrated in the accompanying drawings, and finally pointed out in the appended claims.

In the drawings:

Figure 1 is a plan view of carton material scored, cut and perforated in accordance with my invention.

Figure 2 is a perspective end elevation of the carton showing the end flaps thereof in open position and the pouring spout itself in operative engagement with one of the side walls of the carton.

Figure 3 is an end elevation somewhat similar to Figure 2 but showing more particularly the details of construction of the carton.

Figure 4 is an end elevation of the carton in its completely folded and sealed form.

Referring now more particularly to the drawings:

Reference numeral 1 indicates, generally, carton material properly cut and scored in accordance with my invention, and in readiness to be folded into a carton. The material is formed into side wall panels 2 and 3, and end wall panels 4 and 5. Integral with these wall panels are end flaps 6, 7, 8, 9, 10, 11, 12 and 13. Formed integral with the end wall panel 4, is an auxiliary end wall panel 14, within which I form a de-

pression 15, to be hereinafter more fully described.

All of the said panels are divided by fold lines A, B, C, D, E and F, and all are folded around these division lines as will be hereinafter more fully pointed out.

In large operations where my cartons are to be produced in large quantities, I provide the usual die-cutting machine with an auxiliary cutter which is designed to cut out the irregular portions of the various panels as shown in Figure 1, simultaneously with the cutting operation that forms the blank carton material.

The end flap 10, has one of its corners cut out to form one wall of a pouring spout, indicated, generally, at 16, which consists of two integral walls 17 and 18. The wall 18 is formed at its outermost end with a projection 19, adapted for engagement with the underside of panel 13 when in folded position, to act as a limit stop 20 thereagainst and to prevent over-opening of the spout. The edge of the panel 14 adjacent the wall 18 of the spout, as shown in Figure 1, is beveled as at 20, to act as a guide for the wall 18, and to facilitate its entering a space or cavity formed by the depression 15, between certain of the walls, as will be more fully hereinafter described.

Within the end flap 13, I define, by a perforated line 21, a portion 22, which is adapted to be 30 subsequently broken away around the dotted lines and thereafter to become an integral part of the pouring spout after the seal is broken in the opening operation. This portion 22, is formed with a projection 23, which is defined by a perforated line 24, within the side wall panel 3. The projection 23, forms a lifting tab, and for the convenience of the user, I relieve the end of the tab as at 25, for the insertion of a finger nail or the like for disengaging the tab and the portion 22, from its related panels in the initial opening of the spout. After such opening, the portion 22, remains permanently secured to the wall 18, of the spout.

The folding operation of the material shown 45 in Figure 1 to form my new and improved carton is as follows:

Assuming that the blank material is resting on a table, the end panel 5 is held against the table while the side walls 2 and 3 are drawn upwardly into a vertical position around the folding lines E and F. The auxiliary panel 14, is then folded around the folding line C, into a horizontal position, at which time the end panel 4 is folded likewise into a horizontal position around the fold 55

line D. When thus folding the panel 4, the auxiliary panel 14 will be moved downwardly within the structure thus formed, to lie against the inside surface of the side wall 3. When in this position, it is obvious that the depression 15, in the panel 14 will form a cavity or slot between the inside surface of the panel 3 and the inside surface of the auxiliary panel 14. At this point in the folding operation, the wall 18, of the spout 16, is folded around the fold line C, into a position at right angles to the wall 17. When the wall 18, of the spout is in this position, it is then in alignment with the cavity heretofore described, and indicated at 26 in Figure 3. When in this position, the pouring spout is free to be moved around the fold line B, into a closed or open position. When the spout is being moved into a closed position, the wall 18, of course, will advance into the cavity 26 and be guided and stabilized thereby. With the side and end walls thus folded together, the end flaps are ready to be folded and sealed in the following manner:

The end flaps 7 and 9 are folded inwardly around their fold lines A and then the end flaps 6 and 8 are folded over onto themselves into an over-lapping position and sealed by any approved means, such for instance, as glue or the like. The carton is then brought up into a vertical position to rest upon the sealed end thus formed.

With the carton in a vertical position, the pouring end is now ready to be folded in substantially the following manner: The wall 18, of the pouring spout is first introduced into the cavity 26, and moved downwardly therein until the fold line C, rests squarely along the beveled edge of the auxiliary panel 14. Then the end panels 10 and 12, are folded inwardly. Following this, the panel 11, is folded downwardly against the two inwardly turned end panels 10 and 12. The radius of the cut-out portion of the panel 11, is greater than the radius of the cut-out portion of the panel 10, from which the wall 17, of the pouring spout was formed. Consequently, when the flap 11, overlaps the flap 10, a shelf 27, is formed to support the curvilinear edge of the wall 17, of the spout. Following this, the inside surface of the flap 13, is glued or otherwise pasted, and is then folded downwardly against the assembled end panels just described. With the flap 13 thus in place, it is obvious that that end of the carton is completely sealed. The lifting tab 23 will then appear in the side wall 3.

In opening the carton after the lifting tab has been broken away, around its perforated line 24, a further upward pull exerted upon the tab will cause the portion 22, which now adheres to the wall 17, of the spout, to move thereafter with the pouring spout. From the foregoing, it is obvious that the carton formed in accordance with my invention, is made sift-proof or lead-proof, not only immediately after its initial filling and sealing, but also during all subsequent use, by the com-

plete sealing as just described. Furthermore, after the seal has been broken and the spout has been opened and closed any number of times, a sealed relation will still exist along the fold line C of the pouring spout, and the top edge of the wall 4, of the carton, when the two are brought together.

While I have shown a particular form of embodiment of my invention, I am aware that many minor changes therein will readily suggest themselves to others skilled in the art without departing from the spirit and scope of my invention. Having thus described the invention, what I claim as new and desire to protect by Letters Patent, is:—

1. A carton comprising side and end walls and overlapping and sealed end flaps, a pouring spout formed integral with one of said end walls and movable with respect thereto, said pouring spout having two walls, a guideway formed between 20 overlapping portions of said side and end walls and adapted to slidably embrace one wall of said pouring spout.

2. A carton having four side and end walls and overlapping end flaps, an auxiliary wall formed integral with one of said end walls and adapted when folded to overlie one of said side walls, a depression formed in said auxiliary wall to form a space between itself and said abutting side wall, a pouring spout formed integral with one of said 30 end walls and movable with respect thereto along one edge of one of said walls of the pouring spout, the other of said walls adapted to be moved within said depression.

3. A carton having four side and end walls 35 and overlapping end flaps, an auxiliary wall formed integral with one of said end flaps and adapted when folded to overlie one of said side walls, a depression formed in said auxiliary wall to form a space between itself and said abutting 40 side wall, a pouring spout formed integral with one of said end walls and movable with respect thereto along one edge of one of said walls of the pouring spout, the other of said walls adapted to be moved within said depression, and 45 a limit stop formed integral with one wall of said pouring spout to prevent over-opening of the same.

4. In a carton having side and end walls and overlapping end flaps, the combination of an auxiliary end wall formed integral with one or the other of said end walls, a depression formed within the auxiliary end wall, the outer edge of said depression being beveled, a pouring spout having two walls one of which is formed integral with said first mentioned end wall and the lower edge of its opposite wall lying immediately above said beveled edge, said depression forming a guideway when said auxiliary end wall is united with one of said side walls.
